UNITED STATES PATENT OFFICE.

HENRY J. DUNCAN, OF ALPENA, MICHIGAN.

HANDLE-MACHINE.

1,160,699.

Specification of Letters Patent. Patented Nov. 16, 1915.

Application filed October 31, 1913. Serial No. 798,490.

To all whom it may concern:

Be it known that I, HENRY J. DUNCAN, citizen of the United States, residing at Alpena, in the county of Alpena and State of Michigan, have invented new and useful Improvements in Handle-Machines, of which the following is a specification.

My present invention pertains to machines for making handles and the like.

10 The general object of the machine is to provide a machine constructed with a view of first boring blocks of stock to a slight depth from the ends thereof through the medium of two opposed boring tools or bits, 15 then completing the production of the bore through the medium of two other opposed boring tools or bits, then roughly reducing the piece of stock to the configuration desired, and then finishing and discharging 20 the completed handle; the operation being continuous so that when some pieces of stock are being subjected to the action of certain working elements of the machine, other pieces of the stock will be subjected to the 25 action of other working elements.

The primary and secondary borings of the pieces of stock are materially advantageous inasmuch as they lessen the liability of cracking of the pieces of stock and breaking of the 30 boring tools, while the roughing and subsequent reduction of the pieces of stock to a finished state are advantageous because they obviate the liability of any handle being discharged from the machine in an unfinished state.

35 The primary and secondary borings and the roughing and subsequent finishing of the pieces of stock, all in the order named are also advantageous inasmuch as they contribute to the evenness of operation of the machine.

With the foregoing in mind, the invention will be fully understood from the following description and claims when read in 45 connection with the accompanying drawings, in which:

Figure 1 is an end elevation of a machine constructed in accordance with my invention. Fig. 2 is a top plan of the same. Fig. 3 is an elevation of that side of the machine from which the pieces of finished stock or handles are discharged. Fig. 4 is a vertical section taken in the plane of the line 4—4 of Fig. 3. Fig. 5 is a detail view illustrating 50 in diagrammatic manner the primary and secondary borings of a piece of stock prece-

dent to the reduction thereof to a circular form in cross-section.

Similar numerals of reference designate corresponding parts in all of the views of 60 the drawings.

Journaled in the main frame 1 is a drive shaft 2 having a spur gear 3 and a band pulley 4, and also journaled in said frame are longitudinal shafts 5 and 6 having fast 65 thereon spur gears 7, intermeshed with the gear 3 and through which the shafts 5 and 6 are rotated from the shaft 2.

Fixed on each of the longitudinal shafts 2 and 6 are two pairs of cam members 8, and 70 formed in the said cam members 8 are ways 9, disposed as appears in Fig. 1. Also fast on the longitudinal shaft 5 are cams 10 and 11, and fixed on the shaft 2 is a cam 12 for purposes hereinafter set forth.

75 Fixed with respect to and rising from the main frame 1 are uprights 13, Figs. 1 to 4, and pivoted to said uprights is a swinging frame 14 in which is journaled a shaft 15 that bears a band pulley 16 and a plurality 80 of saws 17. The pulley 16 is designed to be connected through a band, (Fig. 3) with a pulley on an overhead drive-shaft. The saws 17 are arranged to slant to a slight extent—i. e., they are arranged at a slight angle to a line extending at a right angle to the shaft 15. Moreover, the saws have collars 85 18, of large diameters, and hence it is feasible to drive them at a high rate of speed so as to reduce the pieces of stock, of rectangular form in cross-section in a short period 90 of time, and this without vibration. The saws are adapted to "wabble" slightly so as to contribute to the expeditious rounding of the pieces of stock, and all of the saws are 95 keyed on the shaft so that they can be arranged, to jointly reduce the pieces of stock to the desired shape and leave little to be done by the knife.

Bolted to the main frame 1 is a bracket 19 100 that is adapted to be raised and lowered according to the size of the handles to be produced, and is also adapted to be adjustably fixed with respect to the main frame. Slidable in the upper portion of the bracket 19 105 are inwardly and upwardly inclined rods 20, and fixed to and movable with said rods is a holder 21 in which is secured in approved manner a knife 22 for the purpose herein-after set forth. An upright lever 23 is fulcrumed at an intermediate point of its length 110 on a suitable support, and at its lower end

said lever is provided with an anti-friction roller 24 that is normally held in yielding manner against the cam 11, and is designed to be moved by said cam to rock the lever. 5 The upper arm of said lever 23 is connected through a link 25 with the holder 21, and hence it will be manifest that incidental to the operation of the machine and the rotation of the shaft 6, the knife 22 will at the 10 proper times be moved inwardly and upwardly and outwardly and downwardly. A retractile spring 26 is preferably the agency employed to yieldingly hold the anti-friction roller 24 against the cam 11. I would also 15 have it understood that I prefer to provide the knife holder 21 with a cap 21^a which is connected through lag screws with the holder 21 and bears on the knife 22, so that the holder solidly supports the knife and prevents vibration thereof. 20

The swinging frame 14 that carries the gang of saws 17 is raised at intervals through the medium of the cam 10 on shaft 6, a vertically-swinging lever 27 fulcrumed at one 25 end and having at its opposite end an anti-friction roller 28 opposed to the said cam 10, and a link 29 interposed between and connecting the lever 27 and the frame 14.

For the purpose of putting pieces of stock 30 on rotary chucks, hereinafter described, and at the same time displacing the formed handles, I provide the guides 30. These guides have downwardly extending arms 31, and as shown in Fig. 3 they are adapted to operate 35 so expeditiously that the knife 22 has ample time to finish the handles. The guides 30, which are movable to and fro longitudinally of the machine have a stroke of approximately half an inch. Said guides are provided 40 with abutments 33, Fig. 4, for the square pieces of stock to bring up against, and the said pieces of stock are retained in the guides although the discharge ends of the guides are large enough for the passage 45 of the turned handles. It will be observed in this connection that as a follower 34, hereinafter described, pushes the bored block to the rotary chucks 35^a hereinafter described, the guides 30 move inwardly, and this before 50 the knife 22 has finished turning the handle, and when the chucks 35^a pull out of the handle, the handle is not permitted to fly, as there is only the one discharge for the handle, and therefore as soon as the chucks 55 release the finished handle the following square piece of stock ejects it, and as soon as said chucks enter the holes in the ends of the square piece of stock, the guides 30 move outwardly off the piece of stock and permit 60 the same to turn about its axis with the chucks. The guides 30 are in their inner positions when a square piece of stock pushes before it a turned handle, and brings up against the abutments 33; it being understood 65 that the said abutments 33 are so con-

structed and arranged as to enable the turned handle to clear the same. The saws 17 then move downwardly to the piece of stock and reduce it to circular form in cross-section, and at the completion of said operation the knife 22 is presented to the piece of stock to finish the production of the handle. 70

I employ two longitudinally - movable spindles 36, Fig. 2, in the inner opposed ends 75 of which are boring tools or bits 37 for making the first or comparatively shallow borings in the ends of the pieces of stocks, and I also employ two higher longitudinally-movable spindles 38 in the inner opposed 80 ends of which are boring tools or bits 39 for completing the bores in the ends of the pieces of stock; the bits 39 being sufficiently long to meet in the middles of the pieces of stock. 85

The spindles 38 and tools 39 are arranged in a higher plane than the spindles 36 and tools 37, and in order to raise the pieces of stock from the lower spindles to the higher ones, I employ the elevator 40, Fig. 4. The elevator 40 is designed to be raised by the cam 12 on the longitudinal shaft 2, through the medium of a lever 42 and links 43; the lever being fulcrumed at one end, and having at an intermediate point of its length 95 an anti-friction roller 44 that is opposed to the cam, and being connected at its other end to the said links 43. At the proper time in the working of the machine the cam 12, lever 42 and links 43 raise the elevator 40. 100 The elevator 40 is provided with two portions 47 and 48; the portion 47 being arranged lower than the portion 48 as shown.

49, 50 and 51 are three platforms; the platform 50 being higher than the platform 49, and the platform 51 higher than the platform 50 in about the proportion illustrated. On the upstroke of the elevator 40, it serves to raise a square block of stock 52, Fig. 4, from the plane of the platform 49 110 to the plane of the platform 50, and also serves to raise a preceding block 52 from the plane of the platform 50 to the plane of the platform 51. 115

53 is a swinging spring-backed clamp designed to hold a block on the platform 49 in position ready to be pushed by another block to a point above the lower portion 47 of elevator 40.

54 is a vertically-swinging spring-pressed clamp designed to hold a block of stock on the platform 50 ready to be pushed by a following block to a position above the higher portion 48 of the elevator 40, and 55 and 56 are the followers complementary to the platforms 49 and 50 respectively. It is to be noted here that the clamp 54 is carried by a pivoted bail-shaped frame 55^a, the said frame being provided in order to enable the follower 56 to move therein to and from a 120 125 130

position immediately back of the clamp 54. The follower 34 hereinbefore alluded to, which follower 34 is complementary to the platform 51, is fixed to and movable by the 5 follower 56.

The followers 55 and 56 are connected through pairs of links 60 and 61 with lever arms 62, Figs. 2 and 4, fast on a rock shaft 63. The said shaft 63 is provided with another arm 64, and the latter is connected through a link 65 with a wrist pin 66 carried by a disk 67 fast on the shaft 2 at one end thereof, Figs. 2 and 4.

The stock is reduced to blocks of the 15 desired length by a saw 70, and is then placed on the upper stretch of a suitably driven belt 71. This belt 71 conveys the blocks to the upper end of a chute 72 by which the blocks are conducted to a point 20 on the platform 49 and in the path of the follower 55.

As will be observed by comparison of Figs. 1, 2 and 3, there are two pairs of longitudinally-movable rods mounted in the 25 main frame 1 at opposite sides of the transverse center of the machine. The rods of the pairs above the shaft 2 are numbered 90 and 91, and the rods of the pairs above the shaft 6 are numbered 92 and 93. The rods 30 90 at opposite sides of the transverse center of the machine, Fig. 2, are provided at their outer ends with links 94 connected with the spindles 36 in such manner that the spindles are adapted to turn in the arms or links 94, 35 and yet are adapted to be moved endwise inwardly and outwardly by said arms 94. The rods 91 are provided at their outer ends with arms 95, connected to the outer ends of the spindles 38 in such manner that the 40 said spindles 38 are moved endwise inwardly and outwardly by the arms 95, and yet are free to turn about their axes in said arms. The rods 92 are provided at their outer ends with arms 93^a, and to said arms are connected the endwise movable spindles 96 of the before-mentioned chucks 35^a; the 45 connections being such that the spindles 96 are free to rotate about their axes in the said arms, and yet are movable endwise by the 50 arms. When desired the connections described between the several spindles mentioned and the arms on the rods by which the spindles are moved inwardly and outwardly may be similar in construction to 55 the corresponding connections disclosed in my Letters-Patent No. 811,281 of January 30, 1906. The endwise movable rods 93 are connected at 97 with the arms 31 of the guides 30. Mounted on the endwise movable rods 90 and 91 are blocks 100 and 101; the blocks 100 being secured by set screws to the rods 90, and movable loosely on the rods 91, and the blocks 101 being affixed by set screws to the rods 91 and movable loosely 60 on the rods 90. The blocks 100 are pro-

vided with anti-friction wheels movable in the ways 9 of the outer cams below said blocks, while the blocks 101 are provided with anti-friction wheels movable in the ways 9 of the cams 8 below said blocks 101, 70 and consequently it will be observed that rotation of the shaft 2 will be attended by inward and outward movements of the spindles 36 and 38 and their boring tools. Fixed by set screws on the rods 93 and 75 loosely mounted on the rods 92 are blocks 103 having anti-friction wheels 105 disposed in the ways 9 of the cams 8 below said blocks 103, Fig. 3, while fixed by set screws to the rods 92 and loosely mounted on the 80 rods 93 are blocks 104 having anti-friction rollers 105 disposed in the ways 9 of the cams 8 that are disposed below the blocks 104. From this it follows that rotation of the shaft 6 will be attended by inward and 85 outward movements of the chucks or centers 35^a and inward and outward movement of the guides 30; the movements of all of the parts being timed as before described. Each of the spindles 36, 38 and 96 is provided 90 with a band pulley as shown so that said spindle can be driven by a belt from an overhead shaft.

When desirable additional guide rods 110 disposed longitudinally of the machine may 95 be employed to prevent springing of the connections between the blocks that are movable longitudinally and the higher elements that are moved endwise of the machine by the said blocks. See in this connection 100 Fig. 1.

It is believed that the general operation of my novel machine will be fully understood from the foregoing and that therefore it is not necessary to reiterate the same. 105

Having described my invention, what I claim and desire to secure by Letters-Patent, is:

1. In a handle producing machine, the combination of opposed rotary chucks, 110 means for rotating said chucks, means for moving the chucks endwise toward and from each other, means for rotating the chucks, means for turning the stock, guides for holding the pieces of stock while the same are 115 being engaged by the chucks and for holding the handle against flying after it is reduced to the circular form in cross-section, said guides having abutments constructed and arranged to prevent forward movement 120 of the unturned pieces of stock and to permit forward movement of the turned pieces of stock or handles of circular form in cross-section, and means for moving said guides toward and from each other. 125

2. In a wood-working machine, the combination of three platforms arranged in different horizontal planes and having their adjacent portions separated by intervening vertical spaces, an elevator having portions 130

arranged in said spaces, means for actuating the elevator, followers, one complementary to each platform, a rock shaft, means for actuating said shaft, an arm fixed to and 5 movable with said shaft, and links interposed between and connecting the three followers and the said arm.

3. In a handle producing machine, the combination of platforms arranged one 10 above the other as they approach the discharge end of the machine, said platforms being spaced apart, a set of boring tools arranged adjacent to the forward end of the rear and lowest platform, a second set of 15 boring tools arranged adjacent to the forward end of the intermediate platform, opposed rotary chucks arranged adjacent to the foremost and highest platform, means for rotating said chucks, means for moving 20 the chucks endwise toward and from each other, means for turning the stock, guides for holding the pieces of stock while the same are being engaged by the chucks and for holding the handle against flying after 25 it is reduced to circular form in cross-sec-

tion; said guides having abutments constructed and arranged to prevent forward movement of the unturned pieces of stock and to permit forward movement of the turned pieces of stock, means for moving 30 said guides toward and from each other, followers movable forwardly and rearwardly, one above each platform, means for actuating said followers, an elevator having portions for raising pieces of stock from the 35 rear platform to the intermediate platform and from the intermediate platform to the upper platform, respectively, clamps arranged above the forward portions of the lower and intermediate platforms and yielding 40ingly pressed downwardly, and means for depositing pieces of stock on the lowest platform in the path of the follower thereof.

In testimony whereof I have hereunto set my hand in presence of two subscribing witnesses.

HENRY J. DUNCAN.
